COMBINED WRISTWATCH AND STRAP

Carlo Maroni, 24 Via Rodolfo Benini, Rome, Italy

Filed Aug. 4, 1971, Ser. No. 169,162

Claims priority, application Italy Feb. 4, 1971

Term of patent 14 years

Int. Cl. D10—02

U.S. Cl. D42—8

FIG. 5

FIG. 6

FIG. 7

FIG. 8

FIG. 9

FIG. 10

FIG. 11

FIG. 12

FIG. 1 is a front perspective view of a combined wristwatch and strap showing my new design;

FIG. 2 is a rear perspective view thereof;

FIG. 3 is a front perspective view thereof showing the bracelet in an open position;

FIG. 4 is a rear perspective view thereof showing the bracelet in an open position;

FIG. 5 is a front elevational view of another embodiment of my new design having a square watch portion;

FIG. 6 is a rear perspective view thereof;

FIG. 7 is a front perspective view thereof;

FIG. 8 is a rear and side perspective view thereof showing the bracelet in an open position;

FIG. 9 is a front elevational view of yet another embodiment of my new design having a rectangular watch portion;

FIG. 10 is a rear perspective view thereof showing the bracelet in an open position;

FIG. 11 is a front perspective view thereof;

FIG. 12 is a rear and side perspective view thereof showing the bracelet in an open position.

All figures are shaded to show the watch cases and bracelets as transparent.

I claim:

The ornamental design for a combined wristwatch and strap, as shown and described.
